**PORTABLE VACUUM PUMP AND
MOTOR COMBINATION**

Walter V. Cropper, Joseph Kregzdy and Joseph A. Le Blanc, Jr., Chicago, Ill., assignors to Precision Scientific Company, Chicago, Ill., a corporation of Delaware

Filed Apr. 28, 1967, Ser. No. 6,883

Term of patent 14 years

(Cl. D65—1)

Fig. 1

Fig. 2

FIG.3

FIG.4

FIG. 1 is a perspective view of a portable vacuum pump and motor combination embodying the design of this invention;

FIG. 2 is a perspective view thereof taken from an upper corner diagonally opposite the front corner in FIG. 1;

FIG. 3 is a top plan thereof; and

FIG. 4 is a bottom plan thereof.

We claim:

The ornamental design for a portable vacuum pump and motor combination, substantially as shown.
